CLAIM

The ornamental design for a torch bracket, as shown and described.

DESCRIPTION

FIG. 1 is a front right perspective view of the design for a torch bracket;

FIG. 2 is a front left perspective view thereof;

FIG. 3 is a rear right perspective view thereof;

FIG. 4 is a rear left perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof;

FIG. 10 is a bottom plan view thereof; and,

FIG. 11 is a rear left perspective view thereof with a torch mounted in the torch bracket.

The broken lines in FIG. 11 illustrating a torch mounted in the torch bracket illustrates environmental structure that forms no part of the claimed ornamental design. The remaining broken lines in the drawings illustrate portions of the torch bracket that form no part of the claimed ornamental design.

1 Claim, 10 Drawing Sheets
